UNITED STATES PATENT OFFICE.

OSCAR C. DEUTSCHER, OF BROOKLYN, NEW YORK.

CONDENSER.

Application filed August 10, 1925. Serial No. 49,160.

This invention relates to condensers, and more particularly to condensers for use in connection with radio receiving apparatus.

The objects of the invention are to provide a condenser of small size and at the same time adapted for large capacity; to enable the capacity to be readily altered by the user of the condenser; to obtain the operating variation by a lateral separation of plates; to provide a movable plate which will swing away from a fixed plate; to enable the movable plate to be operated by a rotatable dial knob; to secure simplicity of construction and operation, and to obtain other advantages and results as may be brought out in the following description.

Referring to the accompanying drawing in which like numerals of reference indicate similar parts throughout the several views, Figure 1 is a front elevation of a panel and dial, showing my invention; and

Figure 2 is a cross sectional view taken on line 2—2 of Figure 1.

In the specific embodiment of the invention illustrated in said drawing, the reference numeral 1 indicates a panel to which my invention is shown applied. In carrying out my invention, the condenser is mounted on one side of the panel, usually referred to as the back of the panel, and a suitable dial and knob are mounted on the other or front side of the panel.

The condenser preferably comprises a base plate 2, herein shown substantially triangular, with outstanding posts 3 for mounting a fixed condenser plate 4 in spaced and parallel relation to the base plate. The base plate is preferably of insulatory material, and the posts 3 are shown herein as separate members from said base plate, although it is to be understood this may be varied if found necessary or desirable. Furthermore, the arrangement is such that the fixed condenser plate may be very readily applied or removed, for purposes hereinafter more fully explained, and preferably so as not to disassemble the remaining portions of the condenser. For this reason, I have shown the posts 3 secured at one end to base plate 2 by screws 5 inserted through the base plate into the posts, and the condenser plate is held to the posts by other screws 6 inserted through the condenser plate into the outer ends of the posts. It may here be noted that both plates are preferably of the same

size and shape, in this instance triangular, and the posts 3 are positioned at the corners of the triangles.

Interposed between the outer or condenser plate 4 and the ends of posts 3 is an insulation or dielectric member 7. It is for purposes of enabling this dielectric member to be interchangeable that I have made the outer or fixed condenser plate 4 readily removable. By substitution of this dielectric member for another, or with its entire omission, I obtain a variation in capacity to suit the needs or wishes of the user. Heretofore the user has had to select from the various condensers on the market the particular one which he thought would answer his purpose, all the way from a two plate to a 45 or more plate condenser, each additional plate giving added capacity. By the present invention, however, the capacity variation is obtained by a change in the dielectric member rather than in an increase or decrease in the number of plates. The dielectric member 7 may be of any suitable material, such as paper, mica, rubber, glass, and numerous other dielectrics, it being preferable that the same be stiff and not too easily torn, broken or damaged, so as to enable the same to be kept, handled and substituted by the user of the condenser. By including the dielectric member 7 between the ends of posts 3 and condenser plate 4, said dielectric is held flat and prevented from sagging or bulging while in use.

Between the base plate and the outer or fixed condenser plate 4 is a movable condenser plate 8 which is arranged to be moved laterally with respect to the fixed plate. That is to say, the movable plate may be moved toward or away from the fixed plate. In the present instance I have shown this lateral movement obtained by swinging the movable plate.

In carrying out this feature of the invention, I provide a bow spring 9 having one end secured to the base plate and the other end secured to the movable condenser plate. This spring is normally U-shaped and retains the corner of the movable plate to which it is attached at substantially the same distance from the fixed condenser plate at all times but at the same time acts as a hinge so the opposite edge of the movable plate may be swung toward and away from the fixed plate. The spring 9 is also suffi-

ciently rigid to prevent any material side movement of the movable plate so it will not at any time engage the metal posts 3.

A suitable outstanding ear 10 is provided 5 on the movable plate for pivotal engagement with a transverse pin on an operating stud 11 the end of which projects toward the movable plate through the panel 1 and base plate 12. Said stud is arranged to slide in and out, 15 and by the pivotal attachment to the plate the plate is swung the desired amount. As shown, the outer or front end of the stud 11 is screw threaded, as at 12, and engages in a threaded socket in a dial knob 13. Said dial knob 13 rotates about a fixed collar 14 shown 20 as having an outwardly projecting circumferential flange 15 underlying the knob 14 and provided with a scale as clearly shown in Figure 1. Said collar is preferably circumferentially grooved at a place within the knob, as at 16, for receiving one or more screws, or the like 17, projecting inwardly from the knob which enables the knob to be 25 rotated with respect to the collar and flange, but prevents separation of those parts. The collar and flange are held in fixed position upon the panel in any suitable manner, the present showing employing a sleeve 18 fast in the collar with a threaded end projecting 30 into the panel and secured by a nut 19. However, other suitable holding means may be used if preferred. It will be observed that since the knob is held against movement toward or away from the panel, rotation of 35 the same will result in the stud 11 being moved in or out, and held at any position where it may be at the time the knob is turned no further. By a proper proportion of parts and pitch of thread, a single 40 revolution of the knob may be sufficient to obtain full swing of the movable plate. It may be added at this time, that by my construction as shown, a straight line frequency 45 is obtained.

45 Obviously detail changes and modifica-

tions may be made in the construction and use of my improved condenser, without departing from the spirit or scope of the invention, and I do not wish to be understood as limiting myself to the exact structure 70 shown except as set forth in the following claims when construed in the light of the prior art.

Having thus described my invention, I claim:—

1. A condenser having a fixed triangularly shaped plate, a movable triangularly shaped plate hinged at its apex to be swung toward and away from the fixed plate, and means for swinging said movable plate. 80

2. A condenser having a fixed triangularly shaped plate, a movable triangularly shaped plate hinged at its apex to swing toward and away from the fixed plate, and a stud pivotally connected to said movable plate for 85 swinging the same.

3. A condenser having a substantially triangular fixed plate, a substantially triangular movable plate hinged at its apex to swing toward and away from the fixed plate, 50 a stud pivoted to said movable plate for swinging the same, said stud being threaded at its end away from the movable plate, and a knob having a threaded socket to receive said threaded stud for shifting the stud by 55 rotating the knob.

4. A condenser having a substantially triangular fixed plate, a substantially triangular movable plate hinged at its apex to swing toward and away from the fixed plate, 60 a stud pivoted to said movable plate for swinging the same, said stud being threaded at its end away from the movable plate, a knob having a threaded socket to receive said stud, and means for enabling said 65 knob to rotate and hold said knob against movement toward or away from the said fixed plate.

OSCAR C. DEUTSCHER.
